GEORGE M. EATON, OF PITTSBURGH, PENNSYLVANIA, ASSIGNOR TO WESTINGHOUSE ELECTRIC AND MANUFACTURING COMPANY, A CORPORATION OF PENNSYLVANIA.

VAPOR-RECTIFIER.

1,166,196.

Specification of Letters Patent. Patented Dec. 28, 1915.

Application filed March 30, 1914. Serial No. 828,182.

To all whom it may concern:

Be it known that I, GEORGE M. EATON, a citizen of the United States, and a resident of Pittsburgh, in the county of Allegheny and State of Pennsylvania, have invented a new and useful Improvement in Vapor-Rectifiers, of which the following is a specification.

My invention relates to mercury vapor rectifiers, and particularly to means for supporting the shielding members which are employed therein to prevent short-circuiting between the anodes.

The purpose of my invention is to provide a structure which may be quickly and easily constructed and assembled, which will rigidly support the shield, and at the same time insulate it thoroughly from the container.

20 In the accompanying drawing, Figure 1 is a view of my shield support, partially in section and partially in elevation; Fig. 2 is an exploded perspective view of the main member of my support, together with one 25 of the bolt-insulating devices; Fig. 3 is a sectional view of the bolt-insulating device, and Fig. 4 is an end view in elevation of the same member.

The metal cover of a mercury vapor rectifier is shown at 5, carrying an anode 7, and insulated therefrom by an insulating bushing 8. In order to protect the anode from short circuits and other improper arcing, it is surrounded by a cylindrical shielding member 9, preferably of metal. In order to support the shield 9, I provide a ring shaped member 6 of some refractory insulating material, such, for example, as porcelain and provided with several equally spaced openings 10. Seated in the openings 10 are bushings 11, each of which is provided with a shoulder 12 and with a flange 13 dependent therefrom. The bushings are each flattened on their exterior surfaces, as shown at 14, and these flattened portions are adapted to coact with similar flattened portions 15 in the openings 10 so that the bushings are restrained from turning in the openings. The shield member 9 is provided with a flange 17 at its upper end, the flange being co-extensive in width with the lower face of the member 6, except at the openings 10, where it is notched away, as shown by the dotted lines 18—18 55 in Fig. 2. In assembling the device, the

member 6 is placed against the lower face of the cover 5, the shield 9 is placed against the lower face thereof, as shown by dotted lines 18, the bushings 11 are inserted in the openings 10, the shoulders 12 engaging flange 17, and the bolts 16 are then inserted through the bushings 11 and screwed into the cover 5, thus holding the entire assemblage firmly in place. In order to prevent the fracture of the vitreous members, by reason of expansion and contraction, a compressible locking washer 19 is placed under the heads of bolts 16.

The shield-supporting means above described is adapted to maintain the shield member 9 at a fixed distance from cover 5 and insulates it thoroughly therefrom, and the dependent flanges 13 prevent any possibility of arcing between shield member 9 and bolts 16.

Since the flange 17 is deeply notched, where engaged by the insulating members 11, it is impossible for it to rotate about its longitudinal axis, thus insuring that any arcing openings therein will remain in the same relative location with respect to the other anodes of the rectifier.

Having thus described my invention, what I claim is:

1. An insulating support for an electrode shield comprising a ring-shaped member of insulating material, supporting means therefor, and insulating means for the supporting means, a portion of the shield being clamped between the insulating means and the ring-shaped member.

2. An insulating support for an electrode shield comprising a ring-shaped member of insulating material having upper and lower bearing surfaces, bolts projecting through spaced openings therein, insulating bushings for the said bolts having exterior lugs, a portion of the shield being clamped between said lugs and the ring-shaped member.

3. An insulating support for an electrode shield comprising a ring-shaped member of insulating material having upper and lower bearing surfaces, bolts projecting through spaced openings therein, insulating bushings for the said bolts having exterior lugs, and depending flanges to screen the bolts from the shield.

4. An insulating support for an electrode shield comprising a ring-shaped member of

- insulating material, supporting means there-
for, and insulating means for the support-
ing means, a portion of the shield being
clamped between the insulating means and
the ring-shaped member, there being a posi-
tive engagement between the shield and the
supporting means, so that the former is pre-
vented from rotating with respect to the
electrode.
- 10 5. An insulating support for an electrode
shield comprising a ring-shaped member of
insulating material having upper and lower
bearing surfaces, bolts projecting through
spaced openings therein, insulating bush-

ings for the said bolts having exterior lugs, 15
a portion of the shield being clamped be-
tween said lugs and the ring-shaped mem-
ber, said insulating bushings being located
in notches in the shield, so that the latter is
positively prevented from rotating with re- 20
spect to the electrode.

In testimony whereof, I have hereunto
subscribed my name this 26th day of Mar.,
1914.

GEORGE M. EATON.
